UNITED STATES PATENT OFFICE

2,008,872

DRIVE PULLEY FOR BUTTONHOLE STITCHING MACHINES

George Minkowitz, New York, N. Y.

Application February 6, 1935, Serial No. 5,168

3 Claims. (Cl. 74—567)

This invention relates generally to buttonhole stitching machines and has reference particularly to improvements in a cushioning device incorporated in the driven or fast pulley of the machine to soften or cushion the impact of the stopping operation.

My invention is a further development of the buffering spring arrangement fully described in United States Letters Patent No. 541,276.

10 Buttonhole stitching machines operate at a considerable speed and in order to bring the stitching mechanisms to an absolute rest at the completion of a certain number of stitches, a stop motion device of the general type shown in 15 United States Letters Patent No. 743,213, has been devised and cooperates with the driven pulley to arrest movement thereof on the completion of the buttonhole. The impact created by the sudden stopping of parts operating at so 20 great a speed, must be cushioned and this has been done heretofore by a yieldable connection between the fast pulley and a cam which receives the stop motion device, the connection being a buffer spring which is actually an arcuately 25 shaped helical metal member, and which as a consequence is subject to all of the disadvantages inherent in metal springs, i. e., crystallization of the material and breakage in the coils when subjected to sudden and severe strains. 30 In factories where large numbers of these buttonhole stitching machines are in use, a staff of mechanics is constantly in attendance to make replacements of broken springs, so many of them being fractured during the course of operations. 35 Not only is a machine temporarily out of commission while a replacement of the spring is being made, but one or more extra stitches may have been taken by the machine in its failure to stop due to the broken spring and as a result the buttonhole is likely to be imperfect. Up to the 40 present time no suitable substitute for the buffer spring has been discovered and the users of this type of machine have been obliged to content themselves with replacements in order to keep the machines in operation.

45 The present invention is contemplated to overcome the difficulty outlined above and has for its object to provide rubber or other suitable cushioning members as a substitute for the more or less fragile buffer springs originally used in these machines.

50 A further object of this invention is the use of a suitable balance medium embodied in the driven pulley, whereby off-center weight carried by the main shaft is maintained in balance.

I accomplish these objects by means of the embodiment of my invention hereinafter described, set forth in the claims and illustratively exemplified in the accompanying drawing, in which,

5 Figure 1 is a side elevational view of a buttonhole stitching machine embodying my improved cushioning device;

Figure 2 is an elevational view of the face of a driven pulley with a portion of the cover plate 10 broken away;

Figure 3 is a substantially longitudinal sectional view of the pulley taken on lines 3—3 of Figure 2; and

Figure 4 is another sectional view taken on 15 lines 4—4 of Figure 2.

Referring to the drawing, the buttonhole stitching machine comprises a bed 10 from the rear end of which rises the standard 11 of the bracket arm 12, terminating in a head 13. A reciprocating and vertical needle bar and needle 14 are journaled in the head 13 and receive movement from the wellknown needle jogging mechanism, not shown.

The needle operating mechanism comprises a 25 main shaft 15 journaled within and longitudinally of the bracket arm 12 and projected from the rear end thereof to receive a cam 16 rotating with a driven pulley 17 fast on the shaft 15. Adjacent to this fast pulley 17 is a loose pulley 18. 30

The stop motion device of the present machine comprises a lever 19 pivotally mounted on a center screw 20 tapped in ears 21 on the arm 12 of the machine, said lever carrying a vertically movable rod or plunger 22 cooperating 35 with the cam 16. The rod 22 is pressed upwards and the upper end is fitted to enter a peripheral notch 23 formed in the cam 16 which, as hereinafter described, is yieldably connected with the fast pulley 17 so as to soften or cushion the impact of the stopping motion. 40

The cam 16 is provided with a hub 24, which fits over a sleeve 25 projecting from the outer wall of the fast pulley 17 and which forms part of the sleeve embracing the main shaft 15. The 45 cam 16 rests against the wall of the pulley 17 and carries a crank pin 26 which is axially disposed with respect to the axis of the cam and which enters a concentric arcuate slot 27 in the adjacent wall of the pulley. 50

The pulley 17 comprises a hollow wheel having an external peripheral belt groove 28, center hub 29 projecting from the closed end or wall and having a bore 30 projecting through the sleeve 25, to receive the main shaft 15. The 55

peripheral wall of the pulley is of substantial thickness and is cut away at its outer end to form a shoulder 31 defined by a slight flange forming one side of the belt groove 28. A plate 32 seats 5 in the open end of the pulley against the shoulder 31 and is provided with a center opening to embrace the end of the hub 29, the plate being fixed in closed position by screws driven into the shoulder. The pulley 17 is fixed to the shaft 10 15 by means of a pin 33 which is driven through transverse openings in the shaft 15 and hub 29.

The annular space or chamber inside the pulley is occupied by an arcuate metal block 34 which provides the necessary balance because of 15 its own weight and that of a plurality of lead plugs 35 embedded therein, and which is anchored in the pulley shell by means of two or more pins 36, each of which is carried in a bore 37 drilled to 20 embrace the adjacent walls of the shoulder and block 34.

The block 34 occupies substantially one half of the annular chamber in the pulley shell and the other half embraces the arcuate slot 27 and accommodates a loosely disposed arcuate shaped 25 block piston 38 which is provided with an orifice 39 adjacent one end to receive the crank pin 26 of the cam 16. The block 38 occupies substantially one half the space between the ends of the fixed block 34 and is arranged on the pin 30 26 so as to bring it normally about midway of the space. Arranged in the spaces between the ends of the two blocks are buffer blocks of rubber 40, which fill the spaces and which take up 35 and absorb the impact of the stopping operation of the machine.

In the operation of the device the parts will function, as fully described in United States Letters Patent No. 541,276, the rubber blocks 40 taking the place of the buffer spring of the 40 earlier construction. It has been found in practice that the rubber blocks 40 will absorb the

impact of the stopping operation much more effectively than was ever possible with metal springs and after long use will be still in perfect condition, thus the necessity of replacements is almost completely eliminated and the speed of machines operating with the present invention may be increased beyond anything possible in the original machines. It is also pointed out that all existing machines of this character may be equipped with the present invention by merely substituting the latter for the pulley originally supplied with the device. 5 10 15

Having now described my invention and the manner in which the same operates, what I claim and desire to secure by Letters Patent is: 15

1. A pulley and cam for the stop-motion device of a buttonhole stitching machine, comprising a shell having a closed end and a peripheral belt groove and provided with an annular chamber inside said shell and a block counterweight fixed in the chamber, a block piston connected to the cam and movable in the annular chamber between the ends of the fixed block, and rubber cushion blocks interposed between adjacent ends of the fixed block and block piston to soften the 20 impact of the stopping operation. 25

2. A pulley as claimed in claim 2, including a cover plate attachable to the open side of the shell and disposed over the said blocks. 30

3. A pulley and cam for the stop-motion device of a buttonhole stitching machine, comprising a shell having a closed end provided with an arcuate slot, a peripheral belt groove and an inner semi-annular chamber, a piston block movable in said chamber and connected to said cam through the arcuate slot, and a cushion block filling the space between the end of the piston block and adjacent the end of the semi-annular chamber to soften the impact of the stopping operation. 35 40

GEORGE MINKOWITZ.
